Filed Jan. 29, 1957, Ser. No. 636,905

1 Claim. (Cl. 84—1.26)

This invention relates to electrical musical instruments and particularly to apparatus for producing percussive sounds in such instruments.

Percussive devices for electrical musical instruments generally have means for modifying the wave form of the output tones emitted by the instrument in such a manner that the attack and decay characteristics of the modified tone resemble those of struck or plucked instruments rather than the continuous tone of organs and bowed or blown musical instruments. Such a percussive wave form is generally characterized by having a sharp attack or steep wave front, followed by a gradual but definite decay in amplitude.

It is, therefore, an object of the invention to provide a percussion system for electrical musical instruments which allows a succeeding note to be played with a percussive attack and decay regardless of whether previously struck keys are held down or released.

It is another object of the invention to provide apparatus for controlling the attack and decay envelope of the emitted tones of an electrical musical instrument which may be added as a separate unit to the instrument with which it is adapted to be associated without the necessity of alteration thereto.

It is still a further object of the invention to provide a percussive envelope control system for an electrical musical instrument which requires no key switches when associated with a keyboard instrument other than those normally necessary for continuous tone playing.

It is a further object of the invention to provide a percussion system for electrical musical instruments having means for selectively terminating the decay period of each successive note upon release of a key associated with each note.

It is yet another object of this invention to provide a percussion system for electrical musical instruments having means for repeating each percussive tone at a rapid rate for several cycles each time the system is operated.

It is a further object of the invention to provide apparatus for controlling the attack and decay envelope of the emitted tones of an electrical musical instrument which utilizes an envelope control amplifier valve as a device for shaping the decay portion of the tone envelope.

For a better understanding of the invention, together with other and further objects thereof, reference is made to the following detailed description taken in connection with the accompanying drawings, in which:

FIG. 1 illustrates in box schematic diagram form a preferred embodiment of the invention.

FIG. 2 is an electrical circuit diagram of an embodiment of the invention.

FIG. 3 is an electrical circuit diagram of a modification of the invention.

FIG. 4 is an electrical circuit diagram of another embodiment of the invention.

Referring now to the drawings, the embodiment of the invention shown in FIG. 1, in general, has a pair of input terminals 10 which may be connected to any source of electrical audio signal. It will be understood that although the present invention is shown and described by way of example in association with a keyboard operated, continuous tone instrument, such as an electronic organ; yet, as the system is adapted to be connected to the out-

2

put of any tone generating device, it may be used with any other type of continuous tone, electrical musical instrument. The terminals 10 may be connected directly to the output of the instrument, although, if desired, they may be connected to some intermediate point in the circuitry of the instrument and preferably at a point where the original complex generated wave form exists and before the introduction of formant filters or other wave changing circuits.

10 Terminals 10 are connected to a signal amplifier 12 where the signal is amplified and then fed to a rectifier and filter circuit 14. Rectifier 14 may be any well-known rectifier circuit such as a half-wave diode circuit which is followed by a filter having a time constant of sufficient length to substantially eliminate any existing ripple at the lowest tone frequencies to be used, yet not of sufficient length to delay the rise of the resulting D.C. voltage to a maximum level. The output of rectifier-filter 14 is substantially D.C. and is applied to a circuit comprising capacitor 16 and resistor 18 which is connected to the grid of a pulse amplifier 20 and constitutes a differentiation circuit. When a signal is applied to terminals 10, a D.C. voltage appears at the output of rectifier-filter 14. The leading edge of the D.C. wave causes a sharp pulse to be passed through the differentiator components 16, 18 to the input of pulse amplifier 20. At the conclusion of the pulse, no further signal can appear at the input of pulse amplifier 20 as capacitor 16 cannot carry D.C., even though the player may continue to hold down a key or otherwise feed a continuous tone to terminals 10, thereby causing direct current to remain at the output of rectifier 14.

30 The pulses are amplified by pulse amplifier 20 and pass through coupling capacitor 22 to a relay amplifier 24. Amplifier 24 comprises an electronic valve in whose output circuit a normally open relay 26 is connected so that when a pulse appears at the input of relay amplifier 24, the normally open contacts of relay 26 close but remain closed only for the duration of the narrow pulse fed from pulse amplifier 20 and open when the pulse ends. A suitable D.C. voltage from D.C. supply 28 is connected to one of the relay contacts and the other contact is so connected that when the contacts are closed, the D.C. voltage from supply 28 is applied to a capacitor 30 with associated bleeder resistor 32, both of which are connected to the input of an intensity envelope control amplifier 34, which controls the magnitude or intensity of the output signal. The D.C. voltage from supply 28 applied by relay 26 charges capacitor 30 almost immediately.

40 When the relay contacts open at the conclusion of the actuating pulse, the capacitor 30 begins to discharge through resistor 32 at a rate determined by the time constant of the capacitor-resistor circuit. Capacitor 30 is connected to one of the control electrodes of envelope 55 control amplifier 34 in such a manner that when it is charged, the amplifier operates. As capacitor 30 discharges, the amplifier output decreases proportionately until the cutoff point is reached.

50 For purposes of illustration the same signal source, from which the triggering pulse is developed, is applied to amplifier 34 by means of a line 37 connected to terminals 10. However, it will be understood that the input signal applied to terminals 10 and the signal applied to amplifier 34 may originate from entirely separate sources. For example, the two-foot tones may be used as a source of triggering signals whereas the eight-foot tones may be used as a source of signals whose wave envelopes are percussively shaped. As the output of amplifier 34 is controlled by the charge on capacitor 30, the wave form envelope of the signal appearing across a pair of output terminals 36 connected to amplifier 34 thus assumes a

character corresponding to the variation in charge on capacitor 30. As the charge rises from a zero or negative state, almost immediately, to full charge and then decays gradually, the resultant envelope of a signal appearing at output terminals 36 will be percussive in nature, as requirements of such an envelope are fulfilled by the selective charging of capacitor 30. Thus, the intensity envelope of output tone signals may be selectively shaped by suitably choosing the electrical values of capacitor 30 and associated time constant resistor 32. The output signals obtained across terminals 36 may then be passed through formant filters or other devices so as to obtain any tone color that may be desired.

It will be seen that since a pulse is created each time a signal is added to input 10, even though signals already there exist, a new charge is applied to capacitor 30 in response to activation of relay 26 upon reception of each pulse, thereby causing a percussive envelope to appear for each increment of tone added to those already existing. The novel system is thus based on a principle which utilizes the increments in D.C. voltage rather than absolute values, with each increment providing a separate pulse for operation of the envelope control amplifier 34.

Pulse amplifier 20 is a high gain amplifier and always produces a pulse much larger than is required for the operation of relay 26. Signal amplifier 12 is adapted to receive input signals several times as large as that provided by any single note before saturating or reaching a cut-out point so as to limit its output, so that for any reasonable number of notes played in sequence, a separate percussive attack will be produced for each even though previously played keys are not released.

It will be noted that when a previous key is held down while a second is played, the percussive wave envelope emitted by the pressing down of a certain key causes a repetition of the first tone to appear at the output in addition to the second selected tone, since the signal for the first tone is still being applied to the envelope control amplifier 34. This result is not musically unpleasant when fully present, and, in fact, new and interesting effects are afforded by the repetition of held notes which takes place automatically. On the other hand, the player is not required to allow time for circuit recovery between the playing of one note and the next.

FIG. 2 shows in more detail by means of a schematic circuit diagram, the embodiment of the invention described in general terms above. Signal amplifier 12 comprising a pair of cascade connected valves 40, 42 is connected to input terminals 10 through a potentiometer 38 whose movable arm is connected to the control electrode of valve 40. Potentiometer 38 is adjusted so that the percussion system will function properly when a tone of lowest amplitude is played and also so that a tone of highest amplitude has a level corresponding to a fraction of the amplifier's signal-handling capacities. Valves 40, 42 have conventional anode load resistors 44, 46 respectively and also respective cathode biasing resistors 48, 50 with associated bypass capacitors 52, 54. Anode load resistors 44, 46 are connected to a suitable source of D.C. positive potential 28 which may be the high voltage supply of the organ or other electronic musical instrument with which the percussion system is associated.

The tone signal applied to terminals 10 is amplified by valve 40 and fed to valve 42 for further amplification through a coupling capacitor 56. The amplified signal is then passed to rectifier stage 14 through a coupling capacitor 58. Rectifier stage 14 has a diode 60 connected to capacitor 58 which provides half-wave rectification and which is also connected to a filter circuit comprising capacitors 62, 64 and resistor 66, connected in pi fashion so as to remove substantially all signal frequency ripple at the lowest frequency to be used which, for usual percussion applications, may be 120 cycles per second. The time constant of the pi filter, however, should be

relatively short with respect to the highest possible tone signal repetition period with which the percussion circuit is adapted to be used. The rectifier circuit 14 also has a pair of resistors 68, 70 connected to each electrode of diode 60 to provide correct loading thereof and a return path for the direct current developed by rectifier 14.

Because of the action of diode 60 and its associated pi filter, an essentially D.C. or step function wave is applied to a differentiating circuit comprising capacitor 16 and resistor 18 across which a clamp diode 76 is connected. The output of the differentiating circuit is in the form of a sharp pulse which is formed when the leading edge of the step function or rectified D.C. wave is applied to the differentiating circuit. The sharp output pulse is fed to a control electrode of valve 78 which forms a portion of pulse amplifier 20. Valve 78 has the usual anode load resistor 80 and a cathode bias resistor 82. Clamp tube 76 connected across the output of the differentiating circuit allows only positive going pulses to be applied to the control electrode of valve 78.

For each positive pulse received by the control electrode of valve 78, a negative going pulse is applied to the control electrode of valve 84 of relay amplifier 24, through a coupling capacitor 86. Valve 84 has a grid to ground resistor 88 and a cathode bias resistor 90 whose value is suitably chosen to bias valve 84 so that sufficient current flows therethrough to maintain relay 26, normally energized and normally closed contacts 92, 94 open. Relay 26 is serially connected in the anode circuit of valve 84 and it is, in turn, connected to the positive voltage source 28.

Thus, when a negative voltage appears on the control electrode of valve 84 due to reception of a positive pulse at the input of valve 78, valve 84 is driven to cut-off and relay 26 is deenergized, thus allowing contacts 92, 94 to close. At the conclusion of the pulse received by amplifier valve 78, relay 26 is again energized and contacts 92, 94 open. Terminal 92 is connected to the junction point of voltage dividing resistors 98, which are, in turn, connected to D.C. supply 28, while contact 94 is connected to one terminal of capacitor 30, whose other terminal is connected to ground. Resistor 32 is connected in shunt across capacitor 30 and both of these circuit components are connected through an isolating resistor 100 to the control electrode of valve 102 of envelope control amplifier 34.

The musical tone signal is fed to the control electrode of valve 102 from the output of valve 40 through a coupling capacitor 104. Valve 102 has the usual cathode bias resistor 106 with a by-pass capacitor 107 connected thereacross, and anode load resistor 108. A coupling capacitor 110 is connected to valve 102 so that the output thereof is developed across a load resistor 112 which, in turn, is connected across output terminals 36.

A resistor 114 has one end connected to the positive D.C. supply and the other end connected to the cathode end of bias resistor 106 so as to bias the tube slightly beyond cut-off by the voltage divider action provided by resistors 114 and 106, as long as relay contacts 92, 94 are open. When the relay contacts are closed, due to reception of a negative pulse by relay amplifier 24, a positive voltage whose magnitude is determined by selection of suitable values for voltage divider resistors 96, 98 is applied to capacitor 30, charging it substantially instantaneously. At the termination of the negative impulse applied to amplifier 24, relay 26 is energized and opens contacts 92, 94, thereby allowing capacitor 30 to discharge through resistor 32. This discharge has a selected finite, exponential decay time which may be adjusted by selection of ohmic values for resistor 32.

Charging of capacitor 30 applies a voltage to a control electrode of valve 102 which opposes the bias voltage developed across cathode resistor 106. The opposing control electrode voltage is sufficient to allow valve 102 to conduct and function normally as an amplifier so that

an amplified output signal appears across terminals 36. As the capacitor discharges, the control electrode voltage descends towards zero with a corresponding decrease in anode current and similar decrease in amplification. There is, thus, an almost instantaneous attack and gradual decay of tone output, producing the effect of percussion. It will thus be seen that, even though some of the previously struck keys are held down, an additional note when played, will cause another pulse to appear at the input of amplifier 24, thereby causing the relay 26 to cycle and recharge the capacitor which again begins decaying. Thus a new percussive envelope is initiated whenever a new tone is played.

Although the embodiment shown in FIG. 2 has been described in terms of negative pulses being applied to the input relay amplifier 24, yet pulse polarity may easily be reversed by reversing the polarity of the two diodes 60, 76 and by biasing valve 84 somewhat below the point of relay energization. If contacts 92, 94 are changed from normally closed to normally open, the operation will remain the same as described hereinabove. However, as the amplitudes of the pulses applied to amplifier 24 depend on the signal amplitudes which may vary from note to note, excessive current through the relay 26 and valve 84 may result. Therefore, generally more reliable operation is obtainable with the polarities as shown.

An additional feature of the invention is the provision of a repeat circuit so that relay 26 may be placed in continuous cyclic operation at a selected rate of speed to simulate the effect of instruments which are continuously strummed with a plectrum or the fingers or struck by hammers. This is provided by resistor 116, switch 118, capacitor 120 which are serially connected between the input of valve 78 and the output of valve 84. When switch 118 is closed, a positive feed-back is introduced between valves 78 and 84 which produces oscillations in the usual manner. The frequency of the oscillation may be controlled by suitably selecting values for resistor 116, and capacitor 120, with a rate preferably between 3 and 5 cycles per second.

If desired, a separate oscillator may be employed to provide repetitive positive pulses for amplification by pulse amplifier 20. For example, a suitable oscillator may be a conventional gas discharge, relaxation type oscillator as shown in FIG. 2A. Serially connected between D.C. supply 28 and ground are switch 72, resistor 74, gas discharge tube 75 and resistor 79. A capacitor 77 of suitable value is connected between the junction point of resistor 74, gas discharge tube 75 and ground. When the voltage developed across capacitor 77 reaches a value sufficient to cause tube 75 to ionize the resulting discharge, current passes through resistor 79 and produces a narrow pulse. This pulse voltage is applied to valve 78, so that relay amplifier 24 is pulsed in the same fashion as described above, but repeatedly at a rate dependent upon the time constants of the oscillator circuit. As clamping of the pulses is not necessary when the oscillator circuit is used, a normally closed switch 73, gauged to switch 72 is provided. Switch 73 disconnects the output from diode 76 when switch 72 is closed.

A modification of the present invention is shown in FIG. 3 wherein envelope control amplifier valve 102 is utilized to discharge the tone envelope shaping capacitor. This feature provides for a lengthening of the duration of the tone at a low level in order to add more realism when simulating instruments such as a piano or guitar, which have a fast initial decay but whose tones last a comparatively long time at a low level.

Components shown in FIG. 3 which are identical with those previously shown and described are given like reference numerals.

In the modification shown in FIG. 3, instead of being connected to a source of positive voltage at all times, an anode load resistor 122 is connected to the positive voltage supply 28 through relay contacts 92, 94 which remain

open as long as relay 26 is energized. A decay timing capacitor 124, connected to the junction point between load resistor 122 and a second load resistor 126, is provided so that the decay time constant may be adjusted.

In operation, when a negative pulse is received by relay amplifier 24, relay 26 is deenergized, thereby allowing contacts 92, 94 to close and apply a suitable positive voltage to capacitor 124. Capacitor 124 is charged substantially instantaneously and a positive voltage is applied to the anode of valve 102, thus allowing the signal to be amplified and passed to output terminals 36. When relay 26 is again energized at the termination of the negative impulse, the positive voltage is removed from capacitor 124 and the capacitor discharges through resistor 126 and valve 102. In this manner, the extended time, during which the valve conducts, is achieved. The control electrode of valve 102 is placed at a slight positive potential by means of a connection to voltage dividing resistors 138, 140 to prevent any small leakage of signal from the control electrode to anode which would otherwise occur after the signal decay is completed.

Another embodiment of the invention which is adaptable to electrical musical instruments when it is desired to include the percussion system as an integral part of the entire electronic device is shown in FIG. 4. With this system the components comprising the signal amplifier 12, rectifier 14, and pulse amplifier 20 may be omitted. On the other hand, a switch must be provided for each of the keys of the instrument in order to switchably apply an actuating voltage to relay amplifier 24.

In more detail, the embodiment shown in FIG. 4 has a plurality of single pole, single throw switches 132, each of which is associated with a key of the instrument. One contact of all of the switches is connected in common and, in turn, this common connection is connected to a selected point on a voltage divider 133 which comprises resistors 134, 136, 138 serially connected between the positive voltage supply and ground. Each of the other contacts of switch 132 is connected to an individual resistor 140 which, in turn, has its other terminal connected to like terminals of the other resistors 140. These parallel connected resistor terminals are connected to a second point on voltage divider 133 and may be connected across resistor 136. The transient voltage developed across resistor 138 is applied, upon the closing of one or more of switches 132, to a collector bus 139, through a series capacitor 142, and to the control electrode of valve 84. The voltage divider network 133 is shown for purposes of illustrating a suitable means for supplying a D.C. voltage to each key switch, and it will be understood that any other suitable source of voltage, such as a small battery associated with each key, may be employed and switchably applied to collector bus 139.

The remainder of the circuit is the same as previously described in connection with FIG. 2.

In operation, whenever a key is pressed, the resistor associated with the switch actuated by the selected key is applied in parallel across resistor 136, thereby causing the current flowing through resistor 138 to increase and develop a like increase in the voltage appearing at the ungrounded end of resistor 138. Because of the capacitor 142 connected thereto, only the transient changes in this voltage are applied to relay amplifier 24. These changes in voltage then actuate relay amplifier 24 and associated circuits in substantially the same manner as the output of pulse amplifier 20. Inasmuch as the voltage change applied to the capacitor is essentially the same for every note, a positive change is indicated in FIG. 4 and the contacts of relay 26 are therefore arranged to be normally open with the relay being actuated only upon receipt of a pulse from voltage divider 133. Of course, it will be understood that relay 26 may operate in the same manner as shown and described in FIG. 2 by applying a negative voltage from supply 28 to voltage divider 133. In this case the contacts of relay 26

would be normally closed and valve 84 would be maintained in a conductive condition until a negative pulse was received by its control electrode.

While the present invention has been disclosed by means of specific illustrative embodiments thereof, it would be obvious to those skilled in the art that various changes and modifications in the means of operation described or in the apparatus, may be made without departing from the spirit of the invention as defined in the appended claim.

The inventor claims:

In an electrical musical instrument having musical tone signal producing means, the combination comprising: a first amplifier for said tone signals; means for coupling said first amplifier to said tone signal producing means; means for normally biasing said first amplifier below cut-off; means responsive to an actuating pulse for biasing said first amplifier above cut-off and, after said actuating pulse has terminated, for gradually returning the bias of said first amplifier to a value below cut-off; means for generating said actuating pulse comprising a second amplifier for said tone signals, means for coupling said second amplifier to said tone producing means, means for rectifying signals amplified by said second amplifier to produce a D.C. voltage proportional to the

output of said second amplifier, means for sensing changes in the level of said D.C. voltage and for producing a voltage proportional to said changes, and means for amplifying positive changes so sensed to produce said actuating pulses; and said second amplifier adapted to operate below saturation with respect to a signal level in said musical tone signal producing means corresponding to the simultaneous presentation of a plurality of musical notes; whereby the presentation of any note whether played in a succession of notes or played in legato form increases the signal level to said second amplifier, creates said actuating pulse, and biases said first amplifier above cut-off.
